UNITED STATES PATENT OFFICE.

CHARLES TRUAX, OF CHICAGO, ILLINOIS.

DESIGN FOR A FRAME FOR NEBULIZERS.

SPECIFICATION forming part of Design No. 32,567, dated April 24, 1900.

Application filed March 28, 1900. Serial No. 10,551. Term of patent 14 years.

To all whom it may concern:

Be it known that I, CHARLES TRUAX, a citizen of the United States, residing at Chicago, in the county of Cook and State of Illinois, 5 have invented and produced a new and original Design for a Frame for a Nebulizer, of which the following is a specification, reference being had to the accompanying drawing, forming part thereof.

10 In the accompanying drawing my new design is shown in front elevation.

The essential feature of the design comprises a vertical central standard, extending from which are downwardly-curved portions, 15 pendent from one of which are a number of

flasks. Thus in the drawing there is a vertical central standard A, from which extend downwardly-curved portions B C, with connections D between them, and pendent from the curved portion C are the flasks E. 20

What I claim is—

The design for a frame for a nebulizer, substantially as shown and described.

In testimony whereof I have signed my name to this specification in the presence of 25 two subscribing witnesses.

CHARLES TRUAX.
